CARBURETOR

John Webb Hogg, Llanerch, Pa.

Application June 28, 1940, Serial No. 343,037

7 Claims. (Cl. 261—69)

This invention or discovery relates to carburetors; and it comprises in a carburetor for internal combustion engines and the like a body member having a fuel-air mixing chamber in communication with the intake manifold of an engine, an air conduit through the body member and a fuel conduit including a discharge jet delivering to said chamber, means for supplying fuel to said conduit under pressure, means for establishing differential pressures in the air conduit and in the fuel conduit, a pair of flexible fluid pressure holding members linked to each other, with the facing sides of said members exposed to differential pressure in one of said conduits and the remote sides of the members exposed to differential pressure in the other conduit, valve means in the fuel conduit in operative connection with said linkage and adapted to be opened thereby on increase in differential pressure in the air conduit and closed by differential pressure in the fuel conduit, and a throttle associated with the mixing chamber; all as more fully hereinafter set forth and as claimed.

Carburetors of the so-called floatless type, in which fuel is fed directly under pressure to a mixing chamber for mixture with air to form a charge, are attractive to the internal combustion engine art. They avoid difficulties due to selective evaporation of fuel in float chambers, they can be designed to work in any position since they do not depend on gravity for their operation, and they are inherently compact and simple. However, the practical difficulties in the way of supplying small quantities of fuel under pressure without a float control have proved formidable and few floatless carburetors have met with any degree of success.

In my prior Patent No. 2,004,869 there is disclosed and claimed a carburetor of floatless, direct pressure feed type in which fuel feed is controlled in a particular way by pressures developed in the air flow and in the fuel flow. The carburetor functions well in practice even under conditions where the most drastic requirements must be met, viz., aircraft carburetion.

The present invention relates to improvements in carburetors of the type disclosed in my prior patent, and it provides a carburetor eminently suitable for automobile use where a cheap and simple apparatus is desired, in which proper

fuel-air proportioning is maintained by a very simple arrangement of pressure responsive means. The carburetor achieves to a high degree, in a simple way, the ultimate object of all carburetion; supply to the engine of an accurately predetermined fuel-air mixture under all conditions.

The carburetor includes a body member for attachment to an engine containing a fuel-air mixing chamber with an air passage through the member and a fuel conduit delivering to the chamber, and means for establishing differential pressures in each conduit. These may be orificed members, venturis, pilot tubes, impact tubes (a variation of the pilot tube), or the equivalent. A pair of flexible diaphragms or equivalent deflectable fluid pressure holding members are provided, linked to each other at fixed separation. The proximate faces of the diaphragms are exposed to differential pressure in the air conduit and the remote faces are exposed to differential pressure in the fuel conduit. The diaphragm linkage is directly connected to a fuel valve in such arrangement that increase in fuel differential pressure as a result of increased flow, tends to close the valve, and increase in air differential pressure due to increased flow tends to open it. The result achieved is correct fuel-air proportioning under a wide range of conditions, with a very simple construction, only two diaphragms being required as described to separate the two fluids and to permit the other necessary functions. The construction is such that frictional engagement of parts is or can be obviated, no rubbing of parts on each other being necessary. This is a valuable feature in insuring accuracy of proportioning under widely different operating conditions.

My carburetor usually includes certain additional elements, including an adjustment of the fuel differential pressure establishing means, in addition to the automatic valve, for changing the charge proportions under special circumstances; and also means for adjusting the constriction in the air conduit in accordance with atmospheric temperature and pressure changes. This last means is especially useful in carburetors for airplanes or in other cases where an engine is required to operate under widely variable atmospheric conditions.

In the accompanying drawings I have shown more or less diagrammatically several examples of specific embodiments of apparatus within the purview of the invention. In the drawings, 5

Fig. 1 is a view, partly in central vertical section and partly in elevation, of one embodiment of the invention embodying a single pair of diaphragms as described;

Fig. 2 is a similar view to an enlarged scale 10 of the fuel jet of Fig. 1;

Fig. 3 is a similar view of a modification including additional, balancing diaphragms and also means for varying the amount of constriction of the air flow;

Fig. 4 is a sectional view taken along line 4-4 15 of Fig. 3;

Fig. 5 is a view of a simplified embodiment of the invention in which the diaphragm linkage and part of the fuel conduit are combined as a single element;

Fig. 6 is a view in central vertical section of an embodiment including exterior pressure-responsive flow control means; and

Fig. 7 is a similar view of a modified form of flow control means.

Referring to the drawings, and more particularly to Figs. 1 and 2, the carburetor includes a tubular housing or barrel 10 the upper part of which forms an air conduit and the lower part of which defines a mixing chamber 11. A throttle 12 is provided in the mixing chamber. A pair of diaphragms 13 and 14 is provided, linked together by a rod 15 with stiffening discs 16 and 17 next the diaphragms as shown. The diaphragms are supported from a partition 18 in tube 10, by 30 cylinders 19 perforated at 20. Air flows through the assemblage as indicated by arrows. An orifice 25 in the partition 18 creates a differential pressure in the air flow so that the downwardly exposed face of diaphragm 13 is exposed to higher 35 pressure than the upwardly exposed face of diaphragm 14.

A cap 26 surrounds the upper face of diaphragm 13 defining a chamber 27 put under pressure through a conduit 28 from the fuel line 29, which 40 receives gasoline, etc. under pressure from a fuel pump 30. Conduit 29 delivers at 31 to a corresponding chamber 32 below diaphragm 14; a restricted orifice 33 in housing 109 being interposed in the fuel line as shown, to establish 45 differential pressure therein.

The lower end of rod 15 carries a balanced fuel valve including two valve points 34 and 35 cooperating with a valve body member 36 to control the fuel flow from chamber 32. Fuel leaves the chamber at a jet nipple 37 having a small jet orifice 38. Advantageously, a check valve is provided for this orifice, to prevent leakage when the engine is not running. This valve includes a 50 stem 39 urged upwardly by a spring 40 and having a flaring head 41 to distribute the fuel as a spray.

Adjustment for idling is conveniently made by screw 106, forming a stop for part 35 (Fig. 3).

In operation, assuming the engine to be running, air is drawn in by engine suction flowing the course of the arrows in Fig. 1. The air flow has a tendency to open the fuel valve. Fuel is supplied under pump pressure and the fuel flow tends to close the fuel valve. The net result is a quite constant proportioning of fuel and air despite wide variations in air flow and in pump pressure. The throttle works in the usual way.

The relative proportion of fuel and air is determined by the setting of a needle valve 133 operating in orifice 33. This valve can be controlled 75

manually from the driver's seat by a suitable connection, or, if desired, it can be controlled automatically under the influence of engine speed or other variable, to enrich the mixture at idling speed or when heavy loads are encountered or to make it leaner at some cruising speed range. In Fig. 1 the valve is shown as regulated in accordance with engine speed, through the agency of a governor 100 driven by the engine (not shown) and adapted to move a cam 101 bearing against the pin 102 of valve 133. In Fig. 3 the pin 102 is shown as moved under control of a bimetallic thermostat element 104 responsive to engine temperature. The valve 133 is advantageously constructed with a very narrow taper, say a reduction in diameter of 0.01 inch per inch of length.

A balanced fuel valve as shown in Fig. 1 is sometimes unnecessary; a simple valve suffices for small units (cf. Fig. 7).

20 In the modification shown in Figs. 3 and 4, diaphragms of different size are employed in the fuel pressure responsive means and in the air pressure responsive means. By making the fuel pressure diaphragm smaller, less differential pressure need be established in the air flow. As shown, two small fuel pressure diaphragms 50 and 51 and two larger air pressure diaphragms 52 and 53 are provided, all linked together by rod 54. Housings 55 and 56, supported from the chamber 57 by rods 58, enclose the space between each pair of diaphragms, this space being vented to the air at 59, for balancing purposes. The space above 60 at 59, for balancing purposes. The space above the upper fuel diaphragm is capped by a cover 60 and is connected to the fuel line at 61. The lower fuel diaphragm is covered by a cap 62, communicating through conduit 63 with the enriching valve 109 in the fuel line. Rod 54 operates a fuel valve 34, 35 as in Fig. 1. A conduit 64 leads from the valve to fuel jet 137, shown as placed downstream (on the engine side) of the throttle 12, a construction which has advantages, in certain relations, over the conventional arrangement wherein the fuel jet is upstream with respect to the throttle.

55 Figs. 3 and 4 also serve to illustrate the feature of the invention of varying the constriction in the air flow in accordance with the density of the air being metered. The flow of air across a sharp-edged orifice or other constriction is given by the expression $F=CK_1\sqrt{D/H}$, wherein C is the pipe coefficient of discharge, K_1 is a dimensional constant, D is the density of the air and H is the differential head. The density of air varies with altitude and temperature. In order to keep the flow constant I arrange for varying the discharge coefficient in a reciprocal relation to the density, such that $C\times\sqrt{D}=K_2$ (a constant), thereby making the flow proportional simply to the square root of the differential head;

$$F=K_1K_2\sqrt{H}.$$

60 This end is achieved by varying the area of a sharp-edged orifice in the air flow. An iris diaphragm is provided including a stationary annulus 70, a set of leaves 71 and a movable annulus 72 which determines the diaphragm opening by its angular position. The diaphragm is of a type known per se and its interior construction is not illustrated. A bellows 73, partly filled with air or other gas or with a liquid (not shown) having appreciable vapor tension, is mounted in a chamber 74 opening into the tube 57 and exposed to the incoming air. The moving end of the bellows carries a post 75, supported at 76, bearing a cam 76 operating a pin 77 on the dia-

phragm annulus. The pin is urged against the cam by a spring 79 operating on the diaphragm annulus 72 as shown. The bellows expands and contracts as the air density decreases and increases respectively, and in so doing it tends respectively to increase and to decrease the orifice area of the diaphragm opening. Cam 76 is of such shape that the discharge coefficient varies in an inverse manner to the square root of the density, whereby the relation $C \propto \sqrt{D}$ is maintained constant.

Fig. 5 shows a simplified embodiment of the invention in which the diaphragm-coupling member itself forms part of the fuel conduit, with a reduction in the number of parts. A pair of flexible diaphragms 80 and 81 is provided, enclosed in a housing comprising an hour-glass into which fuel is admitted under pressure at 29 to the space above the upper diaphragm and air is admitted at 85 to the space between the proximate sides of the diaphragms. Air leaves the body at 86 and is shown delivered to an engine supercharger 87. The fuel discharge conduit is shown at 88. The body member is constricted at 89 so as to establish a differential pressure in the air flow. The shape of the body member resembles a Venturi passage but purposely departs from true Venturi construction so that the pressure loss at the constriction 89 will not all be regained by the time the flowing air comes in contact with diaphragm 81.

The diaphragms are coupled by a tube 92 terminating at a restricted fuel orifice 93 above diaphragm 80 and extending below diaphragm 81. The lower end 94 of the tube forms a variable opening valve in conjunction with an adjustable taper-headed pin 95, as shown.

In operation, air flow differential pressure across constriction 89 acting on the diaphragms tends to urge the fuel valve toward open position and fuel flow differential pressure across orifice 93 has an opposite effect. Constant proportioning is provided.

It is sometimes desirable to minimize obstruction to the air flow for the engine by disposing the pressure-responsive devices and valves outside the air conduit proper. Figs. 6 and 7 show such modifications. In Fig. 6 an air conduit or chamber 110 is provided, defining a mixing chamber 111 near one end and having mounted exteriorly thereof a housing 112 separated into three chambers 113, 114 and 115 by two diaphragms 116 and 117 coupled together by a rod 118. Chamber 114 is divided by a partition 119 closely surrounding the rod but leaving a small annular orifice 120. Chambers 113 and 115 are connected through conduits 121 and 122 terminating in the air passage at upwardly turned ends 123 and 124 respectively. The pressure in chamber 115 is maintained higher than that in chamber 113 by virtue of the disposition of these ends 123 and 124. This differential is advantageously enhanced by provision of an orifice 125 in the air conduit, which however need not be much smaller in diameter than the air conduit.

Fuel is supplied through a conduit 29 with a branch 126 leading to the lower part of chamber 114 and a branch leading to the upper part of the chamber, as shown, in communication with the lower face of diaphragm 116. Fuel is discharged through a conduit 127, which communicates with a valve housing 128 cooperating with valve members 129 and 130 on rod 118 as shown. 75

The conduit terminates at a jet 131 in the mixing chamber.

Orifice 120 serves to establish differential pressure in the fuel flow, between the proximate faces of diaphragms 116 and 118. A valve 131 is provided for manually enriching the mixture when desired. An automatically controlled valve as in Figs. 1 and 3 can be substituted for valve 131 if desired.

10 The apparatus of Fig. 6 functions similarly to the embodiments shown in Figs. 1 to 5 and no special description of its operation is necessary.

In Fig. 7, the pressure responsive means and valves are simplified. Housing 140 contains a pair of diaphragms 116 and 117 as in Fig. 6, the proximate faces of which are put under air differential pressure through ducts 121 and 122 and the remote faces of which are under fuel differential pressure. A connecting rod 141 is provided for the diaphragms, terminating in a tapered valve member 142 controlling fuel flow. Fuel is supplied to chamber 115 and thence to chamber 113 through branch 143, with a throttling valve at 144 to establish differential pressure in the fuel flow. Orifice 120 around the rod is made as small as possible without rubbing contact. A slight bleed of air takes place through this orifice but insufficient to affect the operation of the carburetor deleteriously. Fuel leaves the housing at 64. The rest of the carburetor (not shown) is like that of Fig. 6.

15 The operation of the carburetor of Fig. 7 is like that of the preceding embodiments.

The carburetors of the invention can be disposed in any position, and the parts thereof can be varied in their absolute or relative proportions to meet particular requirement. The carburetors are or can be embodied in the usual materials: brass, steel etc. for the metal parts 20 and synthetic rubber or thin corrugated metal for the diaphragms. The embodiments shown are primarily intended for use with gasoline or other liquid fuels but can be readily adapted for use with gaseous fuels.

25 45 What I claim is:

1. In a carburetor of the type described, a body member for attachment to an engine intake, a fuel-air mixing chamber in communication with said member and an air conduit delivering to said chamber a fuel conduit including a discharge orifice delivering to said chamber, means for supplying fuel to said fuel conduit under pressure, orifice means adjustable as to discharge coefficient for establishing differential pressure in the air conduit and means for establishing differential pressure in the fuel conduit, a pair of pressure-responsive members coupled to each other and each adapted to deflect under influence of fluid pressure, the proximate sides 30 of said members being exposed to differential pressure in one of said conduits and the remote sides of said members being exposed to differential pressure in the other conduit, valve means in the fuel conduit in operative driven connection with said coupled members and arranged to be urged thereby toward open position on increase in differential pressure in the air conduit and urged toward closed position by increase in pressure in the fuel conduit, and pressure-responsive means communicating with the air being metered and constructed and arranged to reduce the discharge coefficient of said orifice means on increase in air density and vice versa.
2. In a carburetor of the type described, a hollow barrel for attachment to an engine in-

take and having an air passage extending therethrough to said intake, a fuel-air mixing chamber in the barrel, said barrel being provided with a restricted orifice upstream with respect to said mixing chamber and adapted to establish differential pressure in the air passage, a fuel conduit including a discharge orifice terminating in the mixing chamber, means for supplying fuel to the fuel conduit under pressure, means for establishing differential pressure in the fuel conduit, 10 flexible pressure-responsive means fixed in the barrel upstream with respect to said orifice, flexible pressure-responsive means fixed in the barrel downstream with respect to said orifice, whereby the proximate sides of said flexible pressure-responsive means are exposed respectively to high and low air pressure, means coupling said pressure-responsive means together in mutual driving relation, closure means surrounding the remote sides of said pressure-responsive means, 20 conduit means for supplying fuel from a point in the fuel conduit, upstream with respect to the differential pressure-establishing means therein, to the space between the high pressure flexible means and the closure means therefor, conduit means for supplying fuel, from a point downstream with respect to the fuel differential pressure establishing means, to the space between the low pressure flexible means and the closure means therefor, and valve means in the fuel conduit in operative driven connection with the coupling means and arranged to be urged toward open position on increase in differential pressure across said constriction means and urged toward closed position by increase in differential pressure in the fuel conduit.

3. In a carburetor of the type described, a body member including a fuel-air mixing chamber in communication with an engine intake, a tubular housing having an upstream portion open to the air and a downstream portion open to the intake of an engine and a fuel-air mixing chamber in said downstream portion, means in the housing for establishing differential pressure between the upstream portion and the downstream portion, a pair of spaced diaphragms, one small and one large, disposed in the upstream portion of the housing and a pair of spaced diaphragms, one small and one large, disposed in the downstream portion thereof with the large diaphragms of the two pairs facing each other, the proximate faces of the near diaphragms of the two pairs being exposed to air pressure in the conduit upstream and downstream of the differential pressure establishing means, means coupling said two pairs of diaphragms together, means enclosing the space between each pair of diaphragms and the outer face of the outer diaphragms, vents leading

from said spaces between each pair of diaphragms to the open air, a fuel conduit with branches leading to the spaces surrounding the outer faces of the diaphragms, differential pressure establishing means in the fuel conduit between said branches, 5 a valve in the fuel conduit operatively coupled to the diaphragm coupling means, and a fuel jet in said mixing chamber delivering fuel from the valve thereto.

4. In an engine carburetor of the type described comprising a hollow body member including a fuel-air mixing chamber delivering to the intake of an engine, an air conduit and a fuel conduit delivering to the mixing chamber, a valve in the fuel conduit and means responsive to air pressure operatively connected to the valve; the improvement comprising orifice means in the air conduit adjustable as to discharge coefficient means responsive to differential pressure across said orifice means and operatively connected to the fuel valve, and a pressure responsive means exposed to the atmosphere and operatively connected to said orifice means whereby to vary the discharge coefficient of the orifice in inverse quadratic relation to the density of the air.

5. In a carburetor, a tubular body member opening at one end to the intake of an engine and at the other end to a supply of air, means within said member for establishing differential pressure in air flowing through the member, a pair of coupled diaphragms supported within the body member with their proximate sides exposed to air upstream and downstream with respect to said means, a fuel conduit terminating at a discharge jet within the body member, valve means in the fuel conduit in operative connection with the coupled diaphragms and adapted to be urged toward open position on increase in air differential pressure, means for establishing differential pressure in the fuel conduit and means for applying the higher fuel differential pressure to the remote face of the diaphragm exposed to the higher air pressure, and the lower fuel differential pressure to the remote face of the other diaphragm, whereby a substantially constant fuel-air mixture ratio is provided, additional differential pressure establishing means in the fuel conduit and means for controlling said means whereby a temporarily richer or leaner mixture can be provided.

6. The carburetor of claim 2 wherein the pressure-responsive means are single flexible diaphragms.

7. The carburetor of claim 2 wherein the pressure-responsive means are double spaced diaphragms and the spaces intermediate the diaphragms are vented to the atmosphere.

JOHN WEBB HOGG.
